UNITED STATES PATENT OFFICE.

HERMAN J. BOELTER, OF LITCHVILLE, NORTH DAKOTA.

COLTER-CLEANER.

1,080,677.

Specification of Letters Patent.

Patented Dec. 9, 1913.

Application filed March 31, 1913. Serial No. 758,019.

To all whom it may concern:

Be it known that I, HERMAN J. BOELTER, a citizen of the United States, of the town of Litchville, in the State of North Dakota, 5 have invented certain new and useful Improvements in Colter-Cleaners, of which the following is a specification.

This invention relates to improvements in scrapers for roller colters and its object is to 10 produce a device of this class that is adapted to be attached to the tines of the bifurcated bar by which the colter is carried, and which is provided with adjustable cleaning or 15 scraping surfaces adapted to engage either face of the colter as it rotates and remove any foreign substances adhering thereto.

With the foregoing and other objects in view the invention consists in the combination and arrangement of parts to be herein- 20 after fully described in the following specification, pointed out in the claims and illustrated in the accompanying drawing which forms a part of said specification and in which—

25 Figure 1 is a side elevation of my improved colter cleaner in position. Fig. 2 is a front elevation of the same. Fig. 3 is a plan of Fig. 2. Fig. 4 is a rear elevation. Fig. 5 is a vertical section taken on line 5—5 30 of Fig. 4.

Like reference characters indicate corresponding parts throughout the several views.

1 is the colter and 2 its shaft journaled in the tines 3, 3.

35 4, 4 and 5, 5 are U-shaped braces, threaded on their extremities, which engage the tines 3, 3 to support thereupon the bifurcated shield 6. Spacing blocks 7 disposed between the tines 3 and shield, within the braces, retain the latter in an adjusted position with 40 relation to said tines. Secured to either side of the front face of the bifurcated shield by the braces 4, 4 and 5, 5 are flexible metallic bands 8 which pass into the aperture formed 45 by the bifurcation of said shield and engage a metallic strip 9 to which rubber or canvas pieces 10 are secured that comprise the frictional scraping surfaces that rest upon the colter as it rotates.

50 The rear face of the shield is formed with

a pair of integral angular lips 11 disposed in planes parallel to the plane of rotation of the colter and to each of said lips a metallic plate 12 is secured as at 13 by a rivet or other suitable fastening means and said fastening 55 means also engages and supports a pressure spring 14 which presses against the strip 9 which in turn presses the scraper 10 against the colter cleaning the same as it rotates. Should lumps or chunks of clay or other foreign matter adhere to the colter and fail to be removed by the scrapers at the first revolution of the colter the springs 14 will permit the strips 9 and scrapers 10 to adjust themselves to permit passage therebetween 60 of said matter. The springs 14 positioned as illustrated in the drawings afford an independent adjustable scraper surface for each side of the colter face.

What is claimed is:—

1. In a colter cleaner, the combination with the colter tines, of a bifurcated shield adjustably secured thereto, integral angular lips formed on said shield and disposed in planes parallel to the plane of rotation of 75 the colter, a frictional scraper for each lateral face of said colter, flexible metallic bands secured to said shield supporting said frictional scrapers and springs carried by said lips for frictional engagement with the 80 said scrapers.

2. In a colter cleaner the combination with the colter tines, of a bifurcated shield, braces connecting said shield and tines, spacing blocks disposed between said shield 85 and tines, integral angular lips formed on said shield disposed in planes parallel to the plane of rotation of the colter, frictional scrapers for said colter, supporting means connecting said scrapers and shield and 90 flexible adjusting means connecting said lips and scrapers.

In testimony that I claim the foregoing as my own I have hereto affixed my signature in the presence of two subscribing witnesses. 95

HERMAN J. BOELTER.
